UNITED STATES PATENT OFFICE.

GEORGE A. MEELL, OF BYWOOD, PENNSYLVANIA.

DESIGN FOR A RING.

Application filed December 8, 1928. Serial No. 29,164. Term of patent 14 years.

To all whom it may concern:

Be it known that I, GEORGE A. MEELL, a citizen of the United States, residing at Bywood, in the county of Delaware and State of Pennsylvania, have invented a new, original, and ornamental Design for Rings, of which the following is a specification, reference being had to the accompanying drawings, forming part thereof.

In these illustrations, Fig. I is a side view; Fig. II a top plan view; and Figs. III and IV opposite edge views respectively of a ring showing my new design.

I claim:

The ornamental design for a ring, as shown.

GEORGE A. MEELL.
